DOORSTOP

Orville Hinder, Denver, Colo., assignor to Donald
A. Hinder, Colorado Springs, Colo.

Application June 24, 1949, Serial No. 3,527

Term of patent 14 years

(Cl. D10—7)

To all whom it may concern:

Be it known that I, Orville Hinder, a citizen of the United States, residing at Denver, in the county of Douglas and State of Colorado, have invented a new, original, and ornamental Design for a Door Stop, of which the following is a specification, reference being had to the accompanying drawing, forming part thereof.

In the drawing,

Fig. I is a perspective view of a door stop showing my new design,

Fig. II is a plan view of Fig. I,

Fig. III is an end view of Fig. I looking upon the wide end of the door stop, and

Fig. IV is an end view looking upon the tapered end of the door stop.

I claim:

The ornamental design for a door stop, substantially as shown.

ORVILLE HINDER.
